UNITED STATES PATENT OFFICE

117,191

DESIGN FOR A TEXTILE FABRIC OR SIMILAR ARTICLE

Ferdinand W. Mostertz, Philadelphia, Pa.

Application August 14, 1939, Serial No. 86,660

Term of patent 7 years

To all whom it may concern:

Be it known that I, Ferdinand W. Mostertz, a citizen of the United States, residing at Philadelphia, in the county of Philadelphia and State of Pennsylvania, have invented a certain new, original, and ornamental Design for a Textile Fabric or Similar Article, of which the following is a specification, reference being had to the accompanying drawing, forming part thereof.

In the drawing:

The figure illustrates a plan view of a textile fabric showing my design.

The design is characterized by alternate contrasting checks enclosed by horizontal and vertical pile tufts, as shown.

I claim:

The ornamental design for a textile fabric or similar article, as shown and described.

FERDINAND W. MOSTERTZ.
